[57] **ABSTRACT**

A mechanism and method for balancing the forces applied to a continuous-casting mold as it oscillates and thereby minimizing vibration in the supporting structure. The mold is oscillated by cams which engage cam followers on the mold frame. Auxiliary cams engage cam followers on a balancing mass to move the latter always in the opposite direction from the mold. The balancing mass is approximately equal to the mass of the mold and parts which oscillate therewith.

BALANCING MECHANISM AND METHOD FOR CONTINUOUS CASTING MOLDS

This invention relates to a balancing mechanism for an oscillating continuous-casting mold and to a method of balancing forces applied thereto.

In a conventional continuous-casting operation, liquid metal is poured continuously into a water-cooled mold open at the top and bottom. A partially solidified casting emerges from the bottom, after which it solidifies throughout and is further processed as known in the art. The mold is oscillated vertically to prevent the casting from sticking. One form of drive for oscillating the mold includes a pair of driven camshafts journaled to the supporting structure at opposite sides of the mold. Cams on these shafts engage cam followers on the mold frame. Reference can be made to Bode U.S. Pat. No. 3,381,743 for an exemplary showing of an oscillating mold which has a drive of this type. One difficulty has been that the oscillations induce objectionable vibrations in the supporting structure.

An object of the present invention is to provide a balancing mechanism and method which minimize vibration in the supporting structure of a cam-driven oscillating mold.

A more specific object is to provide a balancing mechanism for an oscillating mold, which mechanism includes auxiliary cams on the camshaft and cooperating force-equalizing means, whereby the upward and downward forces on the camshaft are balanced throughout the oscillating cycle.

In the drawing:

The single FIGURE is a diagrammatic isometric view of a portion of a continuous-casting installation equipped with my balancing mechanism.

The installation shown in the drawing includes a multifloor supporting structure, two floors at different levels of which are shown at 10 and 12. An oscillating mold frame 13 is situated above floor 10 at the higher level and carries an open-ended water-cooled mold 14. Horizontal camshafts 15 and 16 are journaled in bearings 17 on floor 10 and are driven from a common drive 18 through bevel gears 19. Camshaft 15 is located under the near side of frame 13 and carries a pair of drive cams 20 near the opposite ends of the frame. Camshaft 16 is located under the far side of frame 13 and carries a pair of drive cams 21. The two camshafts and their drive cams are alike but of opposite hand, and they rotate in opposite directions. Frame 13 has cam followers 22 journaled to its underside at locations to cooperate with cams 20 and 21. As the camshafts 15 and 16 rotate, the cams 20 and 21 act on the cam followers 22 to oscillate the frame 13 and mold 14 vertically. The structure thus far described and its operation are known, as shown for example in the aforementioned Bode patent.

The balancing mechanism of my invention includes a pair of auxiliary cams 25 mounted on camshaft 15 adjacent the respective drive cams 20. The auxiliary cams and drive cams are of similar configuration but displaced 180° from each other; that is, the sectors of the auxiliary cams of maximum and minimum radii are aligned horizontally with the sectors of the drive cams of minimum and maximum radii respectively. The lower floor 12 of the supporting structure carries a pair of upstanding pneumatic cylinders 26 beneath the

respective auxiliary cams 25. Pipes 27 connect the cylinders with a source of compressed air (not shown) through a pressure regulator 28. The cylinders have reciprocable piston and piston rods 29 which carry counterweights 30. Cam followers 31 are journaled to the upper faces of the counterweights at locations to cooperate with the auxiliary cams 25. My balancing mechanism also includes similar parts associated with the other camshaft 16, but I have not repeated the description.

In operation, mold 14 is oscillated vertically in the usual way while metal is introduced thereto to produce a casting. The mold frame 13 and mold 14 move upwardly as the segments of cams 20 and 21 of increasing radii engage the cam followers 22. At the same time the segments of the auxiliary cams 25 of increasing radii engage the cam followers 31 and force the piston rods 29 and counterweights 30 downwardly. The parts move in the opposite directions as the segments of the cams of decreasing radii engage the cam followers. Pressure in cylinders 26 urges the cam followers 31 into engagement with the auxiliary cams 25 throughout the cycle. I maintain a constant pressure in these cylinders by suitably adjusting the pressure regulator 28.

According to my balancing method, I maintain a relation such that:

$$M_1 a_1 + M_2 a_2 = 0$$

where:

30 M_1 = Total mass of frame 13, mold 14, cam followers 22 and all other parts attached thereto.

M_2 = Total mass of counterweights 30, cam followers 31, piston and piston rods 29, corresponding parts associated with camshaft 16, and other parts attached thereto.

35 a_1 = momentary acceleration of M_1

a_2 = momentary acceleration of M_2

M_1 and M_2 are equal; hence $a_1 = -a_2$. The mass of each counterweight assembly equals $M_{1/4}$. The upward force 40 exerted by each of the four cylinders equals twice $M_{1/4}$, so that the forces between the drive cams and their followers are the same as the forces between the auxiliary cams and their followers.

The foregoing relations of mass and pressure are 45 ideal and effectively eliminate vibration in the supporting structure. Nevertheless it is apparent that I can minimize vibrations with reasonable effectiveness using masses and pressures which only approximate this ideal relation. Also I can substitute coil springs for air cylinders to apply upward forces to the counterweights if the mold operates within a narrow speed range.

I claim:

1. In a continuous-casting installation which includes a supporting structure, a mold supported for vertical movement on said structure, camshafts journaled to said supporting structure, drive cams carried by said camshafts, and cooperating cam followers associated with said mold, said camshafts, cams and cam followers constituting a drive for vertically oscillating said mold,

55 the combination therewith of a balancing mechanism operatively connected with said drive to minimize vibrations in said supporting structure brought about by the oscillating movement of said mold, said balancing mechanism comprising auxiliary cams carried by said camshafts, and means carried by said supporting structure and cooperating with said auxiliary cams to receive forces opposing the forces applied to said mold.

2. A combination as defined in claim 1 in which the means cooperating with said auxiliary cams includes upstanding vertically moving rods, counterweights carried by said rods, cam followers carried by said rods and engaging said auxiliary cams, and means urging said rods upwardly.

3. A combination as defined in claim 2 in which the means urging said rods upwardly includes pneumatic cylinders and means for supplying compressed air to said cylinders under regulated pressure.

4. A combination as defined in claim 2 in which the mass of said mold and the parts which oscillate therewith is approximately equal to the mass of said rods, counterweights and parts which move vertically therewith.

5. A combination as defined in claim 4 in which the means urging said rods upwardly includes pneumatic cylinders and means for supplying compressed air to

said cylinders under regulated pressure, the force exerted by said cylinders being approximately twice the second-named mass.

6. In a continuous-casting operation in which liquid metal is poured continuously into a water-cooled mold open at the top and bottom, a partially solidified casting emerges from the bottom, and the mold is cam-oscillated vertically, the improvement which comprises balancing the upward and downward forces applied to said mold in oscillating it, the balancing forces being cam-applied in the opposite direction to the oscillating forces against a mass approximately equal to the mass of the mold and the parts which oscillate therewith, the mass against which the balancing forces are applied being held against the cams with a force approximately twice its mass.
